UNITED STATES PATENT OFFICE.

GEORGE W. FAIR, OF PRIMROSE, PENNSYLVANIA.

DESIGN FOR A GRATE.

SPECIFICATION forming part of Design No. 32,968, dated July 17, 1900.

Application filed June 11, 1900; Serial No. 19,960. Term of patent 7 years.

To all whom it may concern:

Be it known that I, GEORGE W. FAIR, a citizen of the United States of America, residing at Primrose, in the county of Washington and State of Pennsylvania; have invented and produced a certain new and useful Design for a Grate, of which the following is a specification, reference being had therein to the accompanying drawings.

6 This invention relates to certain new and novel designs in grates.

As shown in the accompanying drawings, the grate consists of the novel outline and configuration which will be hereinafter more fully described and specifically pointed out.

In describing the invention in detail reference is had to the accompanying drawings, forming a part of this specification, and wherein like numerals of reference indicate 10 corresponding parts throughout both views, in which—

Figure 1 is a perspective view of my new and original design for a grate. Fig. 2 is a cross-sectional view thereof.

5 Referring to the drawings by reference-

numerals, 1 indicates a rectangular plate having a flat lower face 2 and its upper face formed substantially dome-shaped from the center to the rear end in a curvilinear manner and from the center to the forward end 30 in an inclined manner. The plate 1 is further provided with a series of inverted-V-shaped longitudinally-extending openings 3, terminating at each end into a horizontally-extending solid curvilinear portion 4, and 35 each end of the plate is cut away into a series of inverted -V-shaped recesses 5, forming thereby a series of outwardly-extending V-shaped projections 6.

Having thus fully described my invention, 40 what I claim as new, and desire to secure by Letters Patent, is—

The design for a grate, substantially as herein shown and described.

In testimony whereof I affix my signature 45 in the presence of two witnesses:

GEORGE W. FAIR.

Witnesses:

JOHN NOLAND,
N. L. BOGAN.
